UNITED STATES PATENT OFFICE.

JOHN C. WILSON, OF BOSTON, MASSACHUSETTS.

MESSAGE AND TIME RECORDER.

SPECIFICATION forming part of Letters Patent No. 392,838, dated November 13, 1888.

Application filed January 25, 1887. Serial No. 225,434. (No model.) Patented in France April 7, 1885, No. 163,126; in England March 22, 1887, No. 4,256; in Belgium March 22, 1887, No. 76,812, and in Austria-Hungary November 22, 1887, No. 22,317.

To all whom it may concern:

Be it known that I, JOHN C. WILSON, of Boston, county of Suffolk, State of Massachusetts, have invented an Improvement in Mes-

5 sage and Time Recorders, (patented in England March 22, 1887, No. 4,256; Belgium, March 22, 1887, No. 76,812; Austria-Hungary, November 22, 1887, No. 22,317, and shown and described in certificate of addition dated 10 to March 22, 1887, to French Patent No. 168,136, April 7, 1885,) of which the following description, in connection with the accompanying drawings, is a specification, like letters on the drawings representing like parts.

15 This invention has for its object to construct a message and time recorder adapted to register a message on a strip of paper and record the time of its reception on the strip.

The invention consists in the combination, 20 with a message-recorder comprising registering mechanism and paper-moving mechanism, of a time-stamp consisting of a dial and indicating hands or pointers, and means for actuating the hand-stamp automatically to print 25 the time upon the strip.

The message-receiving instrument preferably consists of an ordinary Morse register adapted to feed the paper strip forward during the time the message is being received; and 30 the time-stamp consists of a dial and an indicator, hand, or pointer, substantially such as shown in United States Patent granted to J. C. Hinchman, No. 265,808, dated October 22, 1882, the essential features of the present invention consisting in automatically operating 35 the said time-stamp to imprint the paper every time the register operates to move the paper forward and record the message.

Figure 1 shows in diagram a portion of an 40 ordinary Morse recorder, and also a portion of the time-stamp, together with means for actuating the time-stamp at each time the recorder operates; Fig. 2, a section of the presser of the time-stamp which presses the paper in contact 45 with the dial, and an electro-magnet for moving the presser; and Figs. 3 and 4, top and under side views of the paper strip upon which the message is recorded.

The recorder *a* and its actuating-magnet *a'*, 50 the paper-strip *a''*, and means for moving it only during the time the message is being re-

ceived, are all substantially as in the ordinary Morse recorders, so need not be herein specifically described.

The time-stamp, composed of a dial, *c*, and 55 indicators, hands, or pointers *c'*, carried by an arbor, *c''*, having its bearings in a bed, *b*, and a presser, *b'*, and suitable actuating devices, (not shown,) are all substantially as in United States Patent No. 265,808, above referred to, 60 said stamp being placed adjacent to the recorder. The paper strip upon which the message is recorded is fed between the dial and the presser. The presser *b* is secured to an armature-bar, *b''*, of an electro-magnet, *b'*, so 65 that when the said magnet is energized the presser *b* will be moved.

I have herein shown a magnet *a'* for the register as included in an electric circuit, 2, containing a battery, 3, said circuit being controlled by the armature 4 of a relay, 5, included in an electric circuit, 6, containing a battery, 7, and a circuit-changer, 8 9. The electro-magnet 10 is also included in the circuit 2. The armature 12 of such electro-magnet 75 has a detent, which enters a notch cut in a wheel, 13, controlled by a suitable spring, so that when the armature 12 is contracted the wheel will be released and thereby rotated. A stud, 14, projecting laterally from a wheel, 80 13, strikes, during the rotation of the wheel, a pin, 15, closing a circuit, 16, containing a battery, 17, thereby causing the magnet *b'* to move the presser against the paper. The strip of paper *a''* is fed forward by the registering apparatus at each time that the recorder operates to receive a message, and it will be seen that at such time the time-stamp will thus be actuated to print the time upon the paper. 85

As herein shown, the message will be recorded upon one side of the paper and the time upon the other side; but while I consider this arrangement most desirable, it is obvious that the time may be printed upon the same side that the message is recorded. By this 90 apparatus a message coming from a distant point may be recorded, together with the time of its reception, upon a single strip of paper, which is moved only at the time the message is received.

I do not herein claim time-printing wheels adapted to be moved into proper position or

set up intermittently, in combination with signal-registering mechanism, also comprising a series of wheels adapted to be moved or set up intermittently, or step by step; nor do I claim time-printing wheels movable continuously, in combination with another wheel adapted to be moved one step forward each time the condition of the circuit is changed to print numbers in succession; and, further, I desire it to be understood that the registering mechanism employed by me is arranged to indicate in code characters any arbitrary signal.

I claim—

- 15 1. In a message and time recorder, the self-starting register comprising a pen and pen-operating magnet constituting the registering mechanism, and paper-moving mechanism adapted to move the paper each time a message is received, combined with a time-stamp comprising time-printing indicators for indicating the time upon the same paper upon which the signal is recorded, a motor mechanism for moving the time-printing indicators continuously, and an electro-magnet, an electro-magnet included in circuit with the pen-operating magnet which controls the circuit of the time-stamp magnet, a relay which controls the circuit of the pen-operating magnet, and a circuit-changing device at a distant point, which controls the circuit of said relay, substantially as described.
- 20 2. In a message and time recorder, the registering mechanism and paper-moving mechanism, combined with a time-stamp and electro-magnet for actuating it to print the paper, a circuit-changer, 12 13, and the electro-magnet 10, all substantially as described.
- 25 3. In a message and time recorder, the registering mechanism and paper-moving mechanism, combined with a time-stamp comprising a dial, *e*, and movable indicators or hands

co-operating therewith, and a presser, the paper to be printed moving between the dial and presser, and an electro-magnet for said presser, 45 substantially as described.

4. In a message and time recorder, the self-starting register comprising a pen and pen-operating magnet constituting the registering mechanism, and paper-moving mechanism 50 adapted to move the paper each time a message is received, combined with a time-stamp comprising motor mechanism for moving the time-printing indicators continuously, motor mechanism controlling the operation of said time-stamp to print the time upon the paper, and a releasing-lever for said motor mechanism, and an electro-magnet included in circuit with the said pen-operating magnet for controlling the said releasing-lever, substantially 60 as described.

5. In a message and time recorder, the pen and pen-operating magnet constituting the code-registering mechanism, and paper-moving mechanism adapted to move the paper each 65 time a message is being received, combined with a time-stamp comprising time-printing devices and a presser or platen, the paper upon which the signal is recorded moving between the said time-printing devices and the platen, 70 an electro-magnet controlling the operation of said time stamp, and a circuit-changing device for the circuit of said electro-magnet, and an operating-magnet for said circuit-changing device included in circuit with the register- 75 magnet, substantially as described.

In testimony whereof I have signed my name to this specification in the presence of two subscribing witnesses.

JOHN C. WILSON.
